CONTINUOUS ROTARY CARTON PERFORATING MACHINE

Kenneth L. Crabtree, Fairfield, Maine, assignor to Keyes Fibre Company, Portland, Maine, a corporation of Maine

Application March 17, 1954, Serial No. 416,873

15 Claims. (Cl. 164—99)

This invention relates to perforating machines and particularly to perforating machines for providing a perforated line on a container or carton.

The particular type of container with which this invention is primarily concerned is the thick paper or cardboard type which can be used in unitary form or which may be formed into segments each of which can be used separately as a small container.

Among the objects of the present invention is the provision of a novel perforating machine and method for use with light-weight cartons that are awkward to handle and properly guide because of their lightness.

Other objects and advantages of this invention will be more readily appreciated as the same becomes better understood by reference to the following detailed description when considered in connection with the accompanying drawings wherein:

Fig. 1 is a side elevational view of a machine embodying the invention.

Fig. 2 is a detailed top plan view of the lower portion of the front section of the apparatus shown in Fig. 1 some of the parts being removed in the interest of clarity,

Fig. 3 is a similar top plan view of the rear portion of the structure shown in Fig. 1.

Fig. 4 is a partial section of the machine of Fig. 1 with the work feed and unloading elements not shown.

Fig. 5 is a sectional view taken on line 5—5 of Fig. 1.

Fig. 6 is a sectional view taken on line 6—6 of Fig. 5.

Fig. 7 is a fragmentary side elevational view of a portion of the driving mechanism of the machine of Fig. 1.

Fig. 8 is an enlarged fragmentary detailed view of some of the teeth of the upper gear shown in Fig. 7,

Fig. 9 is a top plan view showing a portion of the feeding mechanism of the machine of Fig. 1,

Fig. 10 is a side elevational view of the structure shown in Fig. 9 with some associated elements also illustrated,

Fig. 11 is a view partly in elevation and partly in section, of the work-removing mechanism of the apparatus of Fig. 1, taken on line 11—11 of Fig. 2.

Fig. 12 is a top plan view of a carton that can be perforated on the machine of Fig. 1,

Fig. 13 is a top plan view showing the carton of Fig. 12 in closed position, and

Fig. 14 is a side elevational view of the perforating elements of the machine of Fig. 1.

Referring more specifically to the description and drawings wherein similar reference characters refer to similar parts, there is shown a frame generally designated 10 comprising an upper standard 11 and a lower base portion 12. The standard and base are preferably, although not necessarily, made of angle bar construction.

Rotatably positioned between bearings 14 and 16 on base 12, is a shaft 18. And desired type of drive means may be used to rotate the shaft, a drive sprocket 19 being here illustrated as connected to the shaft, this sprocket being, in turn, connected through a chain drive to a drive sprocket 20 driven by actuating means, not shown. Centrally mounted on shaft 18 is a drum 21 and on this drum

2

as best shown in Fig. 4, is provided a plurality of male dies 22, here shown as being four in number, with each die being ninety degrees offset from its adjacent dies. Each of these dies has a top configuration shaped to receive the pre-formed cartons constituting the workpieces to be perforated. In addition, each of the dies 22 is mounted on a platen 24 through which extends a plurality of adjusting screws 26, these screws being positioned to support a group of blocks 28 set in an elongated recess extending centrally through the length of the die. Each of the screws 26 is, itself, held in place by a set screw such as indicated at 30 in Fig. 6. Positioned in a central recess in the die 22 immediately above the blocks 28 are a plurality of knives 32 best shown in Figs. 5 and 14, the cutting edges of the knives extending radially outward from the top surfaces of the die by an amount equal to the thickness of the carton 33 which forms the workpiece. The blocks 28 act, in effect, as a broadened portion of each knife to provide a bearing area for the adjusting screws 26. Ventilating openings 27 are shown as provided in the blocks 28 and in depending bar 29 in which the adjusting screws are threadedly received. The knives are held in any radial position of adjustment by clamp screws 34; note Fig. 6. A flange 36 as shown in Fig. 5, is provided at opposite sides of each platen 24 and fixedly mounted on each of these flanges is a hollow bushing 38 which is provided for a purpose to be herein-after described. A gear 40 is mounted at one end of the shaft 18 outwardly of the frame 10.

Rotatably positioned in bearings 42 on the standard 11 is a second shaft 44, above and parallel with shaft 18. The shaft 44 is provided with a pair of spaced wheels or discs 46 and 48 between which there are suspended a pair of diametrically opposed platens 50 and 52. These platens are pivotally secured to the discs by trunnions such as shown at 54 and 56 positioned in bearings formed on arms 51 and 53 secured to the discs. Secured to each of the platens 50 and 52 is a female die 58.

Since the platens 50 and 52 and their associated die members are similar to each other, the description of one will suffice for a description of the other. Viewing, therefore, platen 50 and its associated structure, as best shown in Fig. 6, it is seen that the die 58 is connected to the platen 50 by a bracket 60 the lower flange 62 of which co-acts with the flange 64 on the die 58 to hold the die on the platen even though allowing movement of the die relative to the platen. The die 58 is kept spaced from the platen 50 by a plurality of compressed springs 66 extending into recesses on the lower platen face at one end and into recesses in the upper die face at the other end thereof.

The die 58 is provided with a central slot and extending through this slot is an elongated metal bar or anvil 68, this anvil being positioned so that when the workpiece is clamped between the die 22 and the spring-pressed die 58, the knives 32 will just cut through that portion of the workpiece which lies against the anvil. The anvil is held in place on a movable bearing plate 70 by pins 72 held by set screws 74. The plate 70 is resiliently held by a plurality of heavy springs 76, each of which is positioned between a washer 78 on the plate and a spring follower 80 positioned on the upper walls of bracket 82 clamped to the platen by bolts 84. The tension of the springs 76 are adjustable by adjusting the follower 80 by means of screw 86. These springs are provided only to relieve any overload on the anvil and are not intended to be compressed during the normal cutting operation.

As best seen in Fig. 5, pins 88 depend from the platen and are adapted to be engaged within the bores of bushings 38 upon a predetermined relative rotational movement of the drum 21 and discs 46 and 48, such engagement being for a purpose to be herein-after set forth. Brackets 90 extend laterally from the die 58 and slidably

enclose the pins 88 which thereby act as guide posts for the vertically movable die and its associated parts.

A gear 92 is provided at one end of shaft 44 outwardly of frame 10 and in a position to mesh with gear 40. The gear 92 is mounted on shaft 44 by means of roller bearings 94 but is kept from rotating relative to the shaft by a lock pin 96 extending into an opening 98 formed on the gear hub 100. The lock pin is adjustably mounted in a housing 102 fixed on shaft 44. By this construction when it is desired to let the gear 92 run free of the shaft, the pin 96 may be removed from the opening 98. The gear 92 is here illustrated as being one-half as large as gear 40, the resulting two to one ratio between the gears allowing the two female dies to serve the four male dies.

In order for the male die and the female die to accurately mate with their surfaces parallel and with their center lines coinciding in the same plane through several degrees of rotation on either side of dead center, and in order to provide for relative compressive action between the dies, some point preceding the dead center position is selected as the first point of contact or true alignment of the dies with each other. This point will depend upon the radii of the discs to which the female dies are connected and of the drum to which the male dies are connected. It will also depend on the amount of compressive distance required. In the illustrated machine, this point is 8 degrees from dead center on the drum supporting the male dies and 16 degrees from dead center on the discs supporting the female die. In order to provide for this alignment of the dies, it is necessary to vary the rotational movement of the female die about its axis. This is accomplished by moving the female die along a predetermined path for the space of 16 degrees from the predetermined point. The mechanism for accomplishing this purpose comprises a cam groove 104 in a track fixed to the inside of the frame 10, encircling the shaft 44, and facing inwardly towards the disc 46. This cam is adjustable and is provided with a removable pin 105, which is used to align the cam to the frame at a predetermined dead center position. This pin is withdrawn and the cam is locked in position by any suitable means before starting the machine. A stub shaft 106 extends from each bearing 54 and mounted on each of the stub shafts is a crank arm 108, at the free end of which is rotatably mounted a roller cam follower 110.

The machine is so constructed that the rocking axis about which the female die rocks by cam action is placed in parallel relationship with the radial axis of the lower drum which passes through the center of the lower die during 16 degrees of rotation of the drum, this 16 degrees encompassing 8 degrees before mating of the upper and lower dies and 8 degrees after such mating. If the two shafts 18 and 44 were geared together in a normal manner the only positions at which the rocking axis of the upper die would coincide with the fixed center line of the lower die, would be at dead center and 8 degrees each side of dead center with respect to the shaft 18. However, the peculiar formation of the cam is such at this area as to rock the female die so that the center perpendicular axes of the female and male dies coincide. With conventional gearing, as the dies approach dead center with the rocking axis of the female die moving at a fixed distance from the axis of the shaft 44, the rocking axis lags behind the male die center axis halfway to dead center, then gradually catches up at dead center. The same relative action takes place in reverse as the dies go out of conjunction. In order to force the rocking axis to remain in the same plane as the male die center axis so that the cam can move the female die in alignment with the male die at times during the complete 16 degrees rotational movement of shaft 18, the guide posts 88, which project from the female die enter into the holes in the bushings 38 which are connected to the male die at the initial 8 degrees alignment position. This engagement continues up to the dead center position and 8 degrees beyond this position, finally disengaging at 8 degrees be-

yond the dead center position. In order for this action to take place, the gears 40 and 92 must permit relative motion during the 16 degrees movement of shaft 18 during the die contact period. This is accomplished by machining away a portion 111 of a predetermined number of teeth 112 on the gear 92, a sufficient amount necessary to keep these teeth from firmly engaging the complementary teeth on the gear 40, thereby providing certain amount of lost motion at this time. The engagement between the guide posts and the bushings, in conjunction with the cam action, acts to force the shaft 44 and its associated parts into rotational angular alignment with the shaft 18 and its associated parts where such correlated rotational movement is not already present, the lost motion connection between the gears allowing such action to take place.

The perforation action takes place during the mating position of the male and female dies, the knives being forced through the workpiece by the clamping pressure between the dies. After passing through dead center, the perforating point, the workpiece remains between the dies until they separate, this separation taking place while the dies are still being held in alignment with each other by the guide posts and cam. When disengagement of the guide posts from the bushings takes place at 8 degrees rotation of the shaft 18 from dead center, the dies part, the workpiece remaining on and being carried along by the male die. Shortly thereafter, the workpiece is automatically stripped from the male die by a mechanism to be subsequently described.

In order to maintain a continuous operation of the machine, there must be provided an automatic feeding apparatus as well as an automatic unloading apparatus. The feeding apparatus, which will be described first, comprises an endless belt type of conveyor 114 shown in Figs. 1 and 2, running over a plurality of pulleys, one of which is indicated at 116. The cartons 33, best shown in Fig. 12, comprising pocketed indented sections 117 and 118 and smooth section 119, are carried along by the conveyor 114 while they are in inverted position. It is not necessary to provide any particular spacing between the adjacent cartons on the conveyor nor to have any particular sequence of flow since mechanism is provided at the feeding station to automatically load the cartons on the dies carried by the drum 21.

The cartons are fed from the conveyor 114 onto a second endless belt type of conveyor comprising three belts 120 where they are held from further movement in the path of the dies mounted on the drum 21 by pivotally mounted bars 122 which are spring loaded into article retaining position by torsion springs 124 mounted on shaft 126. The belts 120 are mounted over a plurality of pulleys 128 in the conventional manner, and may be driven in any way desired. Overhead guide bars 129, under the influence of torsion springs 129A, keep the articles in a fixed path.

In order to be certain that each article is positively engaged by the leading edge of a die, a pair of overhead stops 130 secured together by a tie rod 131 are provided to allow each article to proceed into the path of the die at a controlled time in relation to the rotation of the drum 21. Each of these stops 130 comprises a spring-loaded bar which is mounted on shaft 132 rotatably positioned between brackets 133 fixed on the frame. The bars 130 are provided with offset portions indicated at 134, these offset portions being adapted to engage within the slots 136 on the leading edges of the cartons 33. The stops 130, under the influence of torsion springs 137, act to retain the cartons out of the path of the dies until forced out of such retaining position by the action of a cam 138 fixed to and rotating with each die. This camming action occurs when cam 138 comes into a position to engage a cam roller 140 mounted on an arm 142 fixed to a shaft 144. Also mounted on shaft 144 is a crank arm 146 while another crank arm 148 is mounted on the shaft 132 in substantial alignment with crank arm 146.

The shaft 144 is provided with torsion spring 149. The crank arms 146 and 148 are connected by a link 150. As a result when cam 138 acts on roller 140 to rock shaft 144, shaft 132 is also rocked, thereby rocking stop 130 out of position and allowing the article to be brought into pick-up position against stop 122. The cam 138 is so formed that this action takes place immediately prior to the coming of the die to the feeding station. A pair of bent support bars 152, in alignment with stops 130, extend from the frame, these bars 152 being adapted to support the articles as they leave the conveyor 120. Slots 155 are provided in the support bars 152 to allow passage of the stops 130 therethrough when being moved from an inoperative to an operative position.

It should be noted here that the dies 22 are formed so that their leading and trailing edges 22A and 22B extend diagonally to a point, note especially Figs. 4 and 6. This construction enables the die to more positively engage and hold a workpiece as it projects from the loading station.

After the cartons have been fed to the machine and the perforation operation has taken place, the mechanism for stripping the finished articles from the machine comes into play. This stripping mechanism comprises a plurality of stripper bars 156 fixed to the frame. These stationary stripper bars intersect the rotational path of the articles but are adapted to allow the free passage of the dies 22 by passing through slots on the ends of the dies. In addition, pusher fingers 158 are pivotally mounted at the trailing end of each die 22, extending through slots 159. Torsion springs 160 on the pivot shaft 162 tend to keep the fingers 158 in an inoperative position during the greater part of the drum rotation. As the article is being stripped from the die, however, a cam roller 164 attached to an arm 166 mounted on the shaft 162, comes into contact with stationary cam 168 mounted on the frame. This cam acts on the roller to pivot the arm 166 which rocks the shaft 162 causing the pusher fingers to move to a raised operative position behind the die. As each article, therefore, comes in contact with the stationary stripper bars 156, the pivoting pusher fingers 158 push it forward along the stripper bars to a position where it can be engaged by one of the crossbars 170 mounted on an endless chain conveyor 172 extending over sprockets 174 and 176 mounted on shafts 178 and 180. This conveyor 172 is arranged to be driven in timed relation with the drum 21 so that for each article released from a die there is a cross-bar in position to convey it away. The conveyor 172 may be pivotally mounted at one end so that it may be pivoted out of operative position, when it is so desired. This conveyor 172 may feed the finished articles to a stacking device, to a printer for imprinting advertising matter on the smooth outer cover portion of the carton, or to any other handling apparatus.

It should here be noted that, if so desired, the machine may be used to move articles from the feeding apparatus to a printer, stacker or the like, without perforating the articles. When no perforation is required, the machine is stopped momentarily with the two female dies situated in the horizontal plane intersecting the axis of the shaft 44. In this position they cannot contact the rotating male dies. Then clutch pin 96 is unscrewed out of engagement with the gear 92, whereby the gear 92 is allowed to run idle with respect to shaft 44.

Obviously many modifications and variations of the present invention are possible in the light of the above teachings. This machine is not limited to this perforating job, but may also be used for pressing, punching, shearing, molding and other similar operations.

It is, therefore, to be understood that within the scope of the appended claims the invention may be practiced otherwise than as specifically described.

What is claimed is:

1. A perforating machine comprising a conveyor having holding means thereon for positively engaging a work-

piece at a predetermined feeding station and conveying said workpiece to a perforating position, said holding means being provided with perforating means thereon in a position to contact the workpiece at all times during which the workpiece is on said holding means, movable clamping means adapted to move into timed coinciding and compressive relationship with said holding means at said perforating position whereby said perforating means is caused to pierce said workpiece, stripping means movable with said holding means for stripping said workpiece from said holding means, means for actuating said stripping means when said holding means reaches a predetermined unloading station, and conveyor means for removing said workpiece from said unloading station.

2. A carton perforating machine comprising a rotatable drum, a plurality of dies, each having a contoured face substantially complementary to a face of the carton to be perforated, said dies being positioned on the periphery of said drum, a perforating means protruding from said contoured face of each of said dies, a feeding station at one position of rotation of said drum, holding means to positively hold an article at said feeding station in a position to be engaged by a die, said die having a diagonally extending leading edge and being adapted during the rotation of said drum, to engage said article with the contoured face of said die adjacent the contoured face of said article, said die being further adapted to remove said article from said holding means upon continued rotation of said drum and to then move said article to a perforating station, rotatable means moving in timed relation with said drum and peripherally adjacent thereto, a plurality of backing and clamping means on said rotatable means, said rotatable means being adapted to move one of said backing and clamping means into an aligned position complementary to said die and in compressed relationship with the article held thereon, whereby said perforating means is caused to pierce said article, said drum and said rotatable means thereafter causing said die and said backing and clamping means to be removed from one another during rotation thereof, and means to remove the perforated carton from said die upon a predetermined further rotational movement of said drum.

3. The device as defined in claim 2 wherein means are provided on said rotatable means for causing said backing and clamping means, when it reaches a predetermined position relative to said die, to deviate from the former rotational path thereof for a predetermined distance and to assume a path of movement for the length of this predetermined distance whereby that center plane of said backing and clamping means which is radial to the axis of rotation of said rotatable means is coincident with that center plane of said die which is radial to the axis of rotation of said drum.

4. The device as defined in claim 3 wherein support means are provided to rockably support said backing and clamping means on said rotatable means, and wherein said means for causing said backing and clamping means to deviate from the former rotational path thereof comprises a fixed cam track positioned in encircling relationship to the rotational axis of said rotatable means, said cam track being adapted to act upon a cam follower connected to said support means.

5. In a perforating machine for perforating molded pulp articles, a frame, a first shaft rotatably mounted on said frame, means for rotatably driving said shaft connected thereto, a drum mounted on said shaft for rotation therewith, a plurality of dies spaced from one another along the periphery of said drum, each of said dies being rotatably movable from a work feeding station to a work ejecting station, each of said dies having a surface contour substantially conforming to the surface contour of the articles to be worked on, a slot extending centrally through each of said dies, said slot being substantially radial to the rotational axis of said drum, a perforating device removably and adjustably held with-

in said slot and adapted to bear upon an article held on said die, a second shaft rotatably mounted on said frame in spaced, parallel relationship to said first shaft and operative in timed relation therewith, a pair of parallel support members positioned on said second shaft for rotation therewith, a plurality of clamping members rockably supported between said parallel support members, said clamping members each having a contour substantially complementary to that of said dies, a slot extending centrally through each of said clamping members, said last mentioned slot being substantially radial to the rotational axis of said parallel support members, a backing member removably and adjustably positioned in said last mentioned slot, said backing member being adapted to take the pressure of the cutting edge of the perforating device when one of said dies and one of said clamping members have been moved into complementary and compressive position by the relative rotation of said drum and said parallel support members.

6. The device as defined in claim 5 wherein means are provided to maintain an axial alignment between each of said dies and its complementary clamping member, said axial alignment being in a plane which is radial to the rotational axis of said drum, and tangential to the rotational paths of said dies and clamping members, said axial alignment being adapted to occur while said die and its complementary clamping member are in said complementary and compressive position.

7. The device as defined in claim 5 wherein said first shaft is provided with a first gear adapted to mesh with a second gear positioned on said second shaft, whereby said second shaft is driven in timed relation with said first shaft, said second gear being provided with a predetermined number of adjacent teeth which are so constructed as to be free from meshing engagement with the teeth of said first gear while each of said dies is in said axial alignment with its complementary clamping member.

8. The device as defined in claim 5 wherein each of said clamping members comprises a pair of separate parts wherein one of said parts is resiliently urged away from the other, and wherein said backing member is itself backed by a spring-biased plate, the spring biasing said plate being an adjustable compression spring.

9. The device as defined in claim 5 wherein means are provided to maintain an axial alignment between each of said dies and its complementary clamping member, said axial alignment being in a plane which is radial to the rotational axis of said drum, said means comprising a cam which is fixed relative to said clamping members, a cam follower connected to each of said clamping members and adapted to coat with said cam to cause changes of the radial position of its respective clamping member relative to the rotational axis of said drum, and engaging members connected to each of said clamping members and adapted to positively engage with complementary engaging members on each of said dies during a predetermined, timed portion of the rotational movement of the respective dies and clamping members.

10. A feeding mechanism comprising a conveyor, a first stop biased toward a workpiece-retaining position and positioned adjacent the outlet end of said conveyor, rotatable disengaging means to positively disengage a workpiece from said stop, a second stop constructed and arranged to positively retain a workpiece in spaced position from said first stop and out of the rotary path of said disengaging means, and means on said disengag-

ing means adapted to coat with other means connected to said second stop for moving said second stop from the retaining position thereof so as to allow said workpiece to be engaged by said first stop, said means on said 5 disengaging means and said other means connected to said second stop being so constructed and arranged as to cause the movement of said second stop from said retaining position to occur prior to the positioning of said disengaging means in a position to disengage said workpiece from said first stop.

11. The device as defined in claim 10 wherein said disengaging means is a conveyor having spaced disengaging members thereon, each of said disengaging members being adapted to disengage a workpiece from said 15 first stop during movement of said conveyor and to move it toward and then away from a work station.

12. The device as defined in claim 11 wherein each of said disengaging members is provided with a work performing member which is inoperative until said disengaging member reaches said work station, which then 20 performs the work at said work station, and which again becomes inoperative upon leaving said work station.

13. The device as defined in claim 10 wherein said second stop is mounted for pivotal movement on a 25 rotatable shaft, said shaft having a cam follower connected thereto, said disengaging means being movable and being provided with a cam, said cam and cam follower being adapted to coat for the purpose of rocking said rotatable shaft which, in turn, is then adapted to pivot said second stop away from the retaining position thereof.

14. The device as defined in claim 10 wherein said disengaging means is a conveyor having spaced disengaging members thereon, each of said disengaging members 35 being adapted to disengage a workpiece from said first stop during movement of said conveyor, each of said disengaging members being provided with pusher means to push a workpiece away from said disengaging member upon said workpiece reaching a position where it is engaged by a stripper means which acts to retain said workpiece from continued movement with said disengaging means.

15. The device as defined in claim 10 wherein said disengaging means is a conveyor having spaced disengaging members thereon, each of said disengaging members being adapted to disengage a workpiece from said 45 first stop during movement of said conveyor, each of said disengaging members being provided with pusher means to push a workpiece away from said disengaging member upon said workpiece reaching a position where it is engaged by a stripper means which acts to retain said workpiece from continued movement with said disengaging means, said pusher means being rockably mounted on said disengaging member and being connected to a cam follower which is adapted to coat with a stationary cam for the purpose of rocking said pusher means upon said disengaging member reaching a predetermined position relative to said stripper means, whereby said pusher means, during its rocking movement, acts to push a workpiece away from said disengaging member.
